UNITED STATES PATENT OFFICE.

GILBERT R. ELLIOTT, OF BOSTON, MASSACHUSETTS, ASSIGNOR TO HIMSELF AND FREDERICK MORRILL, OF SAME PLACE.

IMPROVEMENT IN GAME-BOARDS.

Specification forming part of Letters Patent No. 136,048, dated February 18, 1873.

To all whom it may concern:

Be it known that I, GILBERT R. ELLIOTT, of Boston, in the county of Suffolk and State of Massachusetts, have invented a new and Improved Apparatus to be used in Playing Games for amusement and recreation; and that the following description, taken in connection with the accompanying drawing forming a part thereof is a full, clear, and exact specification of the construction of the apparatus and of its mode and manner of use. The object of this invention is to provide an apparatus with which games may be played for amusement and recreation, and in the accompanying plate of drawing the apparatus embraced by this invention is illustrated—

Figure 1 being a top view of the revolving disk of the improved game-board; Fig. 2, a perspective view of the same; Fig. 3, a top view; and Fig. 4, a longitudinal section of the board. Fig. 5 is a view of the center-pin.

The apparatus embraced herein is constructed of three elements; first, a bed or board, A, that, concentric with a given center-pin, *a*, has indicated upon it, by stamping, printing, or otherwise, divisions or spaces B. Each division B is distinguished from the others by a character—as, for instance, a letter of the alphabet, or otherwise—and each is provided with a series of sentences or answers, *c*, which, under any one division, B, are pertinent to a question in common with all the answers—as, for instance, question, "Will I succeed in my present undertaking?" answers, "Beyond your expectations," "No; you will not succeed," &c. These sentences C, grouped as stated, are arranged within the circle of spaces B, and each sentence is on a radial line of the board-center, and each is numbered or otherwise marked to distinguish it from the others of the same group—as, for instance, figures from one upward, and the several groups are similarly marked.

Second, a circular disk, D. This circular disk is of a size that, if it be placed on the board A above described, the sentences C arranged on said board A are entirely covered or concealed from view, and the characters used to mark the several divisions B of the board A, as well also as those used to distinguish the sentences one from another, are ex-

posed to view. This disk D at its center is placed upon the center-pin *a* of the board A, and in radial lines with such center. The disk D is divided into a series of spaces, E, that are each marked with a character—as, for instance, a figure corresponding to those employed for distinguishing the separate sentences C of the group of sentences on the board. The disk also has a radial slot or opening, *b*, through it, that is of suitable length and location that, if it be brought over any one of the radially-arranged sentences on the board A, such sentence will be exposed to view for being read. In line with the slot *b* the disk D, at its periphery or edge *f*, has a defined point, *g*, by which the disk can be set to any given one of the characters used to mark the sentences on the board A, the reading of which is desired. In addition to the above, there is arranged on the disk a series of questions, F, distinguished by characters similar to the characters on board A, under which sentences as answers are grouped, and the question under each character is pertinent to answers on the board under a similar character. These questions can be left off of the disk D, and arranged on a distinct sheet from the apparatus.

Third, an index-hand or pointer or arrow, G. This arrow G is placed on the center-pin of the board, to be revolved or whirled with the hand.

In the apparatus shown by the drawing, letters of the alphabet, from A to X inclusive, are the characters employed to distinguish or mark the groups of sentences or answers on the board, and corresponding letters are employed on the disk D against the several questions thereof—that is, the letter A, or B, or C, &c., against the question pertinent or appropriate to the answers on board A, under the same letter. Figures from 1 to 6 inclusive are employed to distinguish the several answers of each group of answers in board A, and, correspondingly, the divisions of disk D are at least six in number, and each division is marked with a figure of the several figures stated, and that figure different from any of the other divisions.

The apparatus above described I call "Zad-
kiel's Mystic Circles," and it is used as follows:

Suppose the question "Have I any or many enemies?" of the disk to be selected as one to be answered by the Mystic Circles. Noting the letter against such question, which, in the present instance, is E, spin the arrow G with the hands, and when it stops note the number of the spaces E of disk at which the arrow points, which suppose is 1. Now turn the disk around, and bring its point or mark *g* to No. 1 of the numbered answers or sentences to space E of the board A, and the sentence of board A, exposed by the slot *b*, is the answer, which is "You are your own worst enemy." Selecting any other question of the disk, and proceeding as before, an answer will be obtained to it, the apparatus thereby affording amusement, recreation, pleasure, and wonderment.

The board A it is intended to make of wood—black walnut being preferable—but other materials may be employed; and the preparation of the board described will be by means of a sheet that is properly printed with the characteristics required; although, as is obvious, other modes could be adopted, as, for instance, by stamping directly upon the board the characteristics; but the mode stated is the most practical and cheap.

The disk D is to be made of card or pasteboard, or other suitable sheet material, and the arrow of any suitable metal or other material.

Although questions have been herein and by the drawing located on the disk D, it is apparent their location has no connection whatever with the apparatus or its use described; but, obviously, by the described location of them space is economized and compactness secured.

In addition to the features of the apparatus above described, I have combined with them still another feature, by which another game can be played, and this game I denominate "Cremorne." This additional feature is in the arrangement of spaces or divisions H in a concentric ring, I. These spaces are forty-eight in number, and are numbered in periods of fives, as, for instance, 0, 5, 10, 15, &c.

In the playing of Cremorne the arrow is used, and, as devised by me, is played as follows—two, three, or four persons can play: When played by two persons each person is to employ two "men," meaning by men the same as in the play of draughts or chess; but when three or four persons play each person is to have one man only. The several men are to be suitably designated by color, or form, or otherwise, to be known readily from each other. The game is commenced by one of the players spinning the arrow, and, after it has stopped, placing his man on the space of the ring I corresponding in number to the

number of disk D at which the arrow stops; as, for instance, suppose the arrow to stop at 6, then his man is placed on the sixth space, counting from space 0. Another player then spins, and places his man as before stated, and so on for each player, when the first to play again plays, and then the second, third, &c., each player, upon each successive play, running his man along over the spaces of the board a number of spaces thereof equal to the number of disk at which the arrow points at each successive spin of the arrow by the player; and the first to thus complete the series of spaces (the several players playing in turn) is the winner or victor.

If a player in making a play finds the space occupied by the man of another player then such man is to be removed, and the player to whom the same belongs, in his next play, is to begin again at the zero-space; or, in other word, start his man afresh.

When a player has his man in a space beyond space 25, if such man should, by a movement of another player, be removed the player to whom such man belongs is to commence at space 25 in lieu of 0, as before.

When only two persons are playing it is to be optional whether the player advance his man already on the board or place his other man on the board, and the game is won when both men of a player have completed the circuit.

The game of Cremorne has no connection whatever with the Mystic Circles, one being played independently of the other; but the combination of Cremorne with the apparatus increases its utility and versatility.

The spaced circle for Cremorne may be arranged on the disk D, but it is preferable as described.

I desire it to be distinctly understood that I do not intend to limit my claim to the combination of the Cremorne spaced circle with the Zadkiel's Mystic Circles; and, also, it may be well to here observe that the arrow may be fixed, and the disk spun instead; but the arrangement described is preferable.

Having thus described my invention, I shall state my claim, as follows:

The board A having center-pin *a*, arrow G, and the divisions or spaces B, each division containing characters arranged and distinguishable from the others, as shown, in the described combination with the disk D having the series of spaces E, slot *b*, and point *g*, the whole constructed and arranged as herein shown, and operating as and for the purpose specified.

GILBERT R. ELLIOTT.
